CLAIM

The ornamental design for a toy pendant, as shown and described.

DESCRIPTION

FIG. 1 is a front elevational view of the toy pendant embodying my new design;

FIG. 2 is a rear elevational view thereof;

FIG. 3 is a right side elevational view thereof;

FIG. 4 is a left side elevational view thereof;

FIG. 5 is a top plan view thereof; and

FIG. 6 is a bottom plan view thereof.

The cord member is shown in fragment in the drawings and is of indeterminate length.
